UNITED STATES PATENT OFFICE.

JOHN THURY, OF NEW YORK, N. Y.

DEVICE FOR PROTECTING STORES AND THE LIKE AGAINST HOLDUP MEN.

Application filed May 12, 1927. Serial No. 190,814.

The present invention relates to devices designed for protection against hold-up men.

In a case of daylight robberies, the parties in charge of a business place are usually covered by a revolver or other weapon by one or more of the robbers, and commanded to hold up their hands with the intention of preventing anyone from sounding an alarm or offering resistance. It has been proposed heretofore to equip business places with a device whereby an alarm is sounded without the use of one's hands. These devices, however, have been found to be ineffective to the extent that the hold-up man, warned by the alarm, in most cases escape before outsiders come to the assistance of the parties in charge of the business place.

The main object of the present invention is to provide a device, whereby "tear-gas" is adapted to be liberated, without the use of one's hands, in the room in which the hold-up takes place, thereby preventing escape of the hold-up men.

Another object of the invention is to produce a device of the character specified, which is simple in construction, efficient in operation, reliable in use, and which permits the employees of a business place to walk around and perform their usual work, but which may be quickly actuated when the employees are surprised by a robber or burglar, without the latter suspecting it in the least degree.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:

Figure 1 is a vertical section taken through a store, in which the improved protecting device is installed; Fig. 2 is a central vertical section taken through a housing containing a tear-gas bomb, the latter

being shown in elevation, the housing being attached to one of the counters in the store; and Fig. 3 is a similar section taken through a modified housing provided with a tear-gas container, the said housing being shown as attached to the ceiling of the store.

In the drawings, the numeral 10 indicates the walls of a store, to which access may be had through a door 11. Adjacent the walls of the store are provided service counters 12, only one of which has been shown in the drawings. These elements have been described for purposes of illustration only, it being obvious that the protecting device is applicable to localities of any other type. The protecting device includes a housing 13, provided with perforations 14. This housing is attached in any suitable manner to one of the service counters. On the inner face of the bottom of the housing are provided pointed projections 15, on which rests a container 16 of fragile material, such as glass, said container being filled with a tear-gas. Above the container is suspended within the housing a weight 17, provided with an eye 18 which projects above its top face, and through the said eye is extended a horizontally disposed pin 19, which projects through a nipple 20 on the wall of the housing. This nipple is exteriorly screw threaded, as shown at 21, the said threads meshing with interior threads of a sleeve 22, the outer end of which is closed, as shown at 23. The pin extends through the said sleeve and is provided within the latter with an enlargement 24. Against this enlargement and against the closed end of the sleeve bears a coil spring 25, which has a tendency to project the pin 19 into the housing 13. In this manner the weight 17 is held in suspended position above the tear-gas container 16.

A little distance above the floor 26 of the store is attached to the back of the counter 12 a horizontally disposed bar 27, which extends substantially throughout the length of the counter, as shown in Fig. 1 of the drawings. This bar is carried by a plurality of arms 28, which are oscillatably mounted in bearings 29 on the back of the counter. To one of the arms 28 is fixed a pin 30, to the latter being attached a wire 31, or like flexible means. This wire runs over one or more guide sheaves 32 and is connected with the pin 19 above referred to. The bar 27 is held in its elevated position, shown in Fig. 1 of

the drawings, by the spring 25 in the sleeve 22.

When a person behind the counter is held up by robbers, he depresses with one of his feet the bar 27, thereby disengaging the pin 19 from the eye 18 or the weight 17. This weight drops thus onto the gas filled container 16, crushing the same so that the tear-gas is liberated. The gas escapes through the perforations 14 into the room, affecting the persons therein so that the hold-up men are unable to escape. With the mechanism herein described is usually associated an alarm, calling the attention of persons outside of the store to the fact that a hold-up is taking place.

In addition to the device above described, there may be mounted upon the ceiling 33 of the store a housing 34, which is open at its bottom. With this housing is associated a pin 19 of the character above described. This pin is connected by a wire 35, or like flexible means, with the pin 30 above referred to. In this instance, the gas filled container 16' is provided with an eye 36,

through which the pin 19 is extended. When the bar 27 is depressed, the pin 19 is disengaged from the eye 36 of the gas filled container 16', the latter dropping to the floor of the store, whereby it is broken and 30 the gas liberated.

The device shown in Fig. 3 may be used independently of the device shown in Fig. 2, or the said two devices may be combined, as shown in Fig. 1 of the drawings. 35

What I claim is:—

A device of the character described comprising a housing open at its bottom, a spring-pressed pin extending into said housing, a fragile gas-filled container loosely mounted upon said pin within said housing, and means for disengaging said pin from said container whereby the latter is adapted to drop through the open bottom of said housing. 40

Signed at New York, in the county of New York, and State of New York, this 24th day of January, A. D. 1927. 45

JOHN THURY.
